UNITED STATES PATENT OFFICE.

WILLIAM F. C. M. McCARTY, OF PHILADELPHIA, PENNSYLVANIA, ASSIGNOR
OF ONE-HALF TO ADOLPH OHL, JAMES McC. CREIGHTON, AND BERNARD
C. LAUTH, ALL OF SAME PLACE.

LIGHTNING-PROTECTOR FOR ELECTRICAL CIRCUITS.

SPECIFICATION forming part of Letters Patent No. 321,235, dated June 30, 1885.

Application filed March 16, 1885. (No model.)

To all whom it may concern:

Be it known that I, WILLIAM F. C. M. McCARTY, a citizen of the United States, and a resident of Philadelphia, Pennsylvania, have 5 invented certain Improvements in Lightning-
Protectors for Electrical Circuits, of which
the following is a specification.

My invention consists of an improved lightning-protector for electrical circuits, to protect telegraphic, telephonic, and other electrical instruments from being burned out by lightning, as fully described and claimed herein-after.

In the accompanying drawings, Figure 1 is 15 a front view of my improved instrument. Fig. 2 is a vertical section on the line 1 2, Fig. 1; and Figs. 3 and 4 are corresponding views of a modified form of my improved instrument.

Referring to Figs. 1 and 2, A is the base of 20 the instrument, and on this are mounted two standards, *a a*, provided at their upper ends with bearings for a transverse shaft, to which are secured two disks or wheels, D D', set at a little distance apart from each other, as convenience may require. Around the peripheries of these two disks are secured transverse connecting-wires *d* of platinum, and in the drawings I have shown them as being made of a continuous piece of wire, *d*, attached to 25 the pins *d'* on the peripheries of the two disks; but any other convenient method of securing the connecting-wires may be adopted. The two disks thus constitute a traversing carrier for the contact-wires *d*.

To the base of the instrument is secured an 30 insulated post, E, Fig. 2, which projects up between the two disks, and is bent into a hook-shape at its upper end, the outer finger of the hook being provided with an adjustable back stop, *e*. To the insulated base, adjacent to this post, is secured a spring finger or arm, F, which tends to make contact with the back stop, *e*. The shaft carrying the disks D D', however, is so acted on by a spring, weight, or other motor as to turn it in the direction of 35 the arrow, Fig. 2, so that the first transverse wire, *d*, coming into contact with the spring-finger F, serves to keep the said finger from contact with the back stop, *e*, as shown in Fig. 45 2, and this is the normal position of the parts.

In Figs. 1 and 2 the motor consists of a spring, G, having a small cord, *g*, coiled around a shaft, B, while the spring is carried by an adjusting-screw, *g'*, mounted at the upper end of a post, H, Fig. 2.

On the top of one of the standards *a* is mounted and electrically connected therewith a binding-post, *p'*, and the spring-finger F is electrically connected to a binding-post, *p*, while the post E is electrically connected to a binding-post, *p''*, to which the ground-wire is attached.

Under normal conditions, one of the transverse wires *d* of the pair of disks bears, as described, against the spring-finger F, and keeps it out of contact with the back stop, *e*, and the current therefore passes from the post *p* through the spring-finger F, wire *d*, disks D D', and post *p'* to the telegraphic or other instrument to be protected. Should a stroke of lightning occur the wire *d*, which then bears 65 against the finger F, will be burned out, and the finger F will fly into contact with the back stop, *e*, and through the post E the current will be immediately grounded, while the rotation of the disks will bring the next transverse wire *d* into contact with the finger F, and thus 70 automatically re-establish the normal condition illustrated in Fig. 2.

In the modification, Figs. 3 and 4, one of the disks, D', is provided on its outer face with a series of insulating-plugs, *m*, arranged at a distance apart proportionate to the relative distances apart of the transverse wires *d*.

On the base is mounted a spring-contact, 85 E', whose outer end bears against the disk D' in the path of the series of annular plugs *m*, and to the base is also secured a fixed finger, F', with which the transverse wires *d* come into contact.

On one of the standards *a* is mounted a binding-post, *p*, which is connected to the line, while the finger F' is connected, through the binding-post *p'*, with the instrument to be protected.

When one of the wires *d* of the pair of disks is bearing against the finger F', the contact-point of the spring E' will be resting on one of the insulation-plugs *m*, and the circuit will be from the post *p* through the frame, disks, 90 95 100

cross-wires d , and finger F' to the binding-post p' .

On the burning out of the cross-wire d this circuit will be broken, and the disks, being released, will be caused to revolve by the spring g , so that the contact end of the spring E' will come into electrical contact with the metallic portion of the disk D' , and the current will be immediately grounded, while the continued rotation of the disk will bring the next cross-wire into contact with the finger F' , and so automatically re-establish the normal condition.

I am aware of the device shown in the French patent of Bertsch, No. 64,114, dated August 17, 1864, and do not claim anything therein shown.

I claim as my invention—

1. A lightning-protector for electrical circuits, consisting of a traversing carrier having a series of contact-wires, a finger in the circuit to make contact with said wires, and an earth-connection to ground the circuit on the burning out of one of said contact-wires, substantially as set forth.

2. A lightning-protector for electrical circuits, consisting of a pair of disks or wheels, transverse connecting-wires, a motor to turn said disks, a finger to make contact with the transverse wires, and electrical connections, substantially as described, to ground the circuit on the burning out of a transverse wire.

3. The combination of a traveling carrier having a series of contact-wires and a spring-finger adapted to be acted on thereby and connected to the line, with a contact-post connected to the ground and with which the spring-finger makes contact when released, substantially as specified.

In testimony whereof I have signed my name to this specification in the presence of two subscribing witnesses.

WM. F. C. M. McCARTY.
